Stillman C. Davis.

UNITED STATES PATENT OFFICE.

STILLMAN C. DAVIS, OF CAMBRIDGE, MASSACHUSETTS.

BLACKBOARD-ERASER.

SPECIFICATION forming part of Letters Patent No. 402,570, dated May 7, 1889.

Application filed May 5, 1888. Serial No. 272,972. (No model.)

To all whom it may concern:

Be it known that I, STILLMAN C. DAVIS, of Cambridge, in the county of Middlesex and State of Massachusetts, have invented a new and useful Improvement in Blackboard-Erasers, of which the following, taken in connection with the accompanying drawings, is a specification.

My invention properly appertains to the class of adjustable hand block erasers used for erasive purposes upon tablets and blackboards employed in all educational institutions, and to all other uses and purposes to which my invention before mentioned may be applicable, and is an improvement upon the invention described in Letters Patent of the United States of America, numbered 254,094, issued to John F. Freese and myself as assignees of Chauncey M. Lothrop, dated February 21, 1882.

It consists of a new and improved method of securing and retaining the fabric or material used for erasive purposes when inserted in the hand block or frame. It simplifies the manner and labor of making renewals of the eraser when such renewals are necessary. It enables me to make use of certain articles of great economy and utility for erasive purposes which it was found impracticable to use before.

In order to a full understanding of the utility, extent, and merit of my invention, for which application is hereby made for Letters Patent, reference is made to the accompanying drawings.

Figure 1 is a longitudinal vertical through-section of the hand block or frame. Fig. 2 shows the plan of the perforated metal plate herein described. Fig. 3 shows a longitudinal vertical section of the perforated metal plate. Fig. 4 shows the manner of applying the perforated metal plate to the pieces of erasive material.

A indicates the frame or body of the eraser, preferably constructed from wood, and in form rectangular, of sufficient thickness to insure strength and durability. The lower or under part of the body A is scarfed away one-half its length, (or, if preferable, the addi-

tional thickness may be obtained by the addition of material united to the part A on the dotted line b,) to admit the attached and duplicated body B, which is secured to the upper body, A, at the point C by leather or other cheap and durable material. At each end of the frames A and B are mortised openings or grooves D D, extending the width of the body.

My invention, for which I make application for Letters Patent, consists in applying to the ends of the pieces of fabric, or whatever material it may be desirable to use for erasive purposes, a narrow strip or band of ordinary tin, zinc, iron, or other metal plate, perforated (or, as it is known to the trade, "stabbed") in the manner shown in Fig. 2. I adopt a method of perforation that produces on the under side of the metal plate a sharp projecting burr similar to the burrs on the tin graters used for household purposes. The strips may be of any desired width, preferably from three-eighths to three-fourths of an inch wide. These strips of perforated metal plate, with the burrs next to the material, are folded or bent around the ends of it, and by subjecting them to a heavy pressure the burrs are forced down into the fabric or other material, securing it firmly and rigidly, in the manner shown in Fig. 4. When thus treated, the pieces of erasive material can be easily and quickly inserted in the grooves D D of the hand block or frame. It greatly facilitates the labor of removing and cleaning the same. It obviates the liability heretofore existing to become loosened and displaced when in use. The labor of making renewals of the erasive material is greatly simplified and reduced. The rigid metal bands serve to support and retain the edges of the fabric in its natural condition and in such a manner as to prevent the previous tendency to ravel, and consequently saves much of the expense heretofore necessarily incurred in stitching the edges in order to retain them.

Having explained the construction and operation of my invention, what I claim, and desire to secure by Letters Patent, is—

1. In a blackboard-eraser, the combination

of an adjustable eraser-strip with pieces of perforated metal plate rigidly attached to the ends, all substantially as set forth.

2. In a blackboard-eraser, the combination 5 of a hand block or frame with an adjustable eraser-strip having attached to each end thereof strips of metal plate perforated in the manner shown, as and for the purpose specified.

In testimony whereof I have signed my name to this specification, in the presence of two subscribing witnesses, on this 30th day of April, A. D. 1888.

STILLMAN C. DAVIS.

Witnesses:

WALTER E. LOMBARD,

FRANK E. BRAY.
